DRILL BIT WITH NONTRACKING ROLLERS

John A. Zublin, Los Angeles, Calif.

Application May 13, 1940, Serial No. 334,809

5 Claims. (Cl. 255—71)

This invention relates to oil well drilling tools, more particularly to the type of bit which involves a revolving carrier having rolling cutters mounted thereon.

5 Bits of the type illustrated in Patent 2,126,079, granted August 9, 1938, cut a pattern in the formation very similar to that shown in Figure 3 of the patent. If the rollers are evenly spaced, and the discs of the cutters are evenly spaced 10 on the rollers, there is a tendency for the carrier to take up such a position with relation to the formation as to cause the rollers to "track," i. e., for the rollers to follow the pattern as the bit rotates. Of course, the pattern is composed of 15 two sets of lines, one set extending spirally downward, and the other set extending spirally upwards, as shown in Figure 3 of the patent referred to, but the two patterns do not obliterate each other in certain types of formation. At 20 attempts to remedy the tendency to track by uneven spacing of the rollers, and uneven spacing of the discs on the rollers, have to some extent limited the tracking tendency, but it is obvious that variation in spacing decreases the amount of 25 cutting edge available, as there is a minimum distance between rollers, imposed by the cutting action on the formation. With these limitations in mind, it is proposed to modify the cutting action of a bit of the type above-mentioned to 30 bring about a more complete breaking up of the pattern than has heretofore been possible.

It is therefore a primary object of this invention to prevent tracking of cutters in a rolling disc bit.

35 It is a further object of the present invention to vary the paths any given roller takes over the formation.

It is a further object of this invention to cause 40 the cutters to take different paths as they proceed over the formation.

It is a further object of the present invention to introduce a variation in the motion of a cutter across the formation to introduce a different cutting action.

45 Referring now to the drawing:

Figure 1 is an elevation, partly in section, of one form of bit embodying the present invention;

Figure 2 is a side view of the bit shown in 50 Figure 1; and

Figure 3 is a diagram of the bottom of a bore being produced by the bit of Figure 1, illustrating the paths of the cutters.

A shank 10 is provided with a pin 11 for engagement with the drill collar and the rest of the

drilling string. A series of reamers, 12, 13 and 14 is mounted on the shank for rotation, in any manner desired. The shown mounting is by means of a series of plates welded into slots in the shank, as fully described in U. S. Patent 5 2,156,444, granted May 2, 1939. These reamers are for the dual purpose of insuring a full gauge bore and for proper positioning of the cutter head with respect to the bore, to cause the head to rotate on the shank.

10 Below the reamers is provided a leg 15, having a bearing support 16 extending therefrom. A sleeve 17 is mounted on the bearing support 16, which sleeve 17 has ball races 18 and a roller race 19 on its outer surface. In order to provide 15 a convenient method of assembly for the ball bearings, there is an opening through the sleeve intersecting each ball race for the insertion of balls, the opening being closed with the plug 20. This plug has its lower portion formed to act as 20 a key, resting in a keyway formed in the bearing support 16, to prevent the sleeve 17 from rotating on the bearing support 16.

A carrier 21, with its inner bore formed to operate with the ball and roller races of the 25 sleeve 17 is mounted on the sleeve 17, and rotates freely therearound. This carrier 21 in turn carries a series of rolling cutters 22 of the type referred to in the above mentioned Patent No. 2,126,079. These rolling cutters 22 have on their 30 faces cutting teeth 23, here illustrated as a series of discs, suitably hardfaced or otherwise treated to make them capable of penetrating the formation being cut. To secure the carrier in place, and also provide additional support for the bearing support 16, a leg 24 is welded or otherwise 35 secured to the shank and carries the support 16 in a hole near its lowermost end.

To this point, the described bit is largely conventional. In Figure 1 it will be noted that line 40 A—A is perpendicular to the bearings between the sleeve and the carrier. Line B—B passes through the centers of the cutters 22, and might be said to represent the plane of the cutters. C—C is the same number of degrees from A—A 45 as B—B, but on the other side. If the carrier 21 is rotated 180 degrees from its position shown in Figure 1, the line through the centers of the cutters would take the position of line C—C, and the cutter would take the position of the dotted 50 circle 23'.

In Figure 3 is shown, in section, the bottom of a bore being produced by this bit. As explained in the patent above referred to, the cutters roll about the hemispherical bowl along a line such 55

as 30. Normally, the following cutters run on lines which can best be described as parallel to line 30, as shown in Patent 2,126,079, and, at the same time, the cutters on the rising side of the 5 carrier cut a series of spirals in the other direction. As was said in the onset, it is sometimes difficult to prevent the cutters from tracking in the pattern as the bit rotates. With the cutters set in other than the plane of A—A, however, each 10 cutter takes, or tends to take, a slightly different path from the others. For instance, the lowermost cutter of Figure 1 will travel over the solid line 30, while the uppermost cutter will, if started 15 from the same point in the hemisphere, travel along the dotted line 31. This is so because the constants which determine the path of the cutter, as for example, the distance of the plane of rotation of the cutter from the axis of the hole, (and, incidentally, from the bit axis) are different 20 for each cutter, the top and bottom cutters of Figure 1 having the two extremes of motion.

It is readily apparent that a fan of lines at comparatively small angles to each other, between 30 and 31, would be most efficacious in 25 obliterating the pattern generated by the rollers as they cut into the formation. In practice, it has been found that the cutters, when arranged as described, exhibit the characteristic wear of 30 cutters working on a patternless, or slightly patterned, hole bottom. At the same time, the bit cuts faster and further before worn out, due to the improved action of the cutters and the diminished tracking tendency of the cutters.

It is to be understood, of course, that the scope 35 of the present invention is to be determined from the appended claims, and not from the description above, which is intended to be illustrative only.

What I claim as my invention is:

1. In an earth boring bit, a shank, a carrier mounted for rotation on said shank, a series of rolling cutters mounted for rotation on said carrier, said cutters being so arranged that their centers are at varying distances from a plane perpendicular to the axis of rotation of the shank. 5

2. In an earth boring bit, a shank, a carrier mounted for rotation on said shank, a series of rolling cutters mounted for rotation on said carrier, 10 said cutters having their axes in a common plane inclined with respect to a plane perpendicular to the axis of rotation of the carrier.

3. In an earth boring bit, a shank, a series of 15 reamers holding said shank with its axis a pre-determined distance from the walls of the bore being produced, a carrier mounted for rotation on said shank, and a series of rolling cutters mounted for rotation on said carrier, said cutters being mounted with their axes in a common 20 plane inclined with respect to the axis of rotation of the carrier.

4. A carrier assembly for earth boring bits comprising a carrier body, a series of cutters mounted for rotation on said carrier body, and bearing 25 means for rotatable mounting of said carrier, said series of cutters being mounted with their axes in a common plane inclined with respect to the axis of said bearing means.

5. A carrier assembly for earth boring bits comprising a carrier body, a series of cutters mounted for rotation on said carrier body, and bearing 30 means for rotatable mounting of said carrier, said series of cutters being mounted with their centers at varying distances from a plane perpendicular to the axis of said bearing means. 35
